UNITED STATES PATENT OFFICE.

H. R. FELL, OF TEXAS, MARYLAND.

LIMEKILN.

Specification of Letters Patent No. 19,023, dated January 5, 1858.

To all whom it may concern:

Be it known that I, H. R. FELL, of Texas, in the county of Baltimore and State of Maryland, have invented a new and useful 5 Improvement in Perpetual Limekilns; and I do hereby declare that the following is a full, clear, and exact description of the same, reference being had to the accompanying drawings, forming part of this 10 specification, in which—

Figure 1, is a front view of a lime kiln constructed with my improvements. Fig. 2, is a vertical central section in the line x, x , of Fig. 4. Fig. 3, shows a vertical 15 central division in the line y, y , of Fig. 4, halves of the kiln being exposed. Fig. 4, is a horizontal section of the lime kiln as in proper condition for operation.

Similar letters of reference in each of the 20 several figures indicate corresponding parts.

The nature of my invention consists in providing a perpetual kiln with two or more air chambers, intermediate between the inner and outer surfaces of the wall of the 25 kiln, when said chambers are constructed and arranged in the peculiar manner hereinafter more fully described.

To enable others skilled in the art to make and use my invention I will proceed to 30 describe its construction and operation.

A, represents a kiln constructed with a circular central chamber B suitable for burning lime-stone and coal together. The basin a , of this central chamber is similar 35 in form to an inverted cone, and has a discharge opening C, through which the manufactured lime discharges.

D, D', represent the air chambers, they are constructed in the building of the wall

of the stack, and present in their horizontal 40 section an annular space a' , intermediate between the inner and outer surfaces of the kiln as shown in Fig. 4, the said space being divided by radial partitions e, e , so as to prevent a continuous revolution of the air, 45 and to render more certain its entrance into the stack. The chamber D, is double the depth of the air chamber D', and has two external inlet passages a^2, a^2 , while D', only has one b . This is necessary in order that 50 sufficient draft be admitted to insure the first burning of the fuel perfectly. The chamber D, is situated near the base of the kiln, while D', is a considerable distance 55 above it. This is necessary in order that air may be supplied by the chamber D', to insure the combustion of the smoke and gaseous products thrown off from the coal.

The draft or air is supplied through flues 60 c, c, c, c , which are made flaring inward or tapering outward as shown at c', c', c', c' , so that the limestone and coal shall not fall back into the air chambers, and also that the air shall be compressed, and the draft shall consequently be more powerful and sudden 65 in its effect.

What I claim as my invention, and desire to secure by Letters Patent, is—

The peculiarly constructed air chambers 70 D, D', intermediate between the inner and outer surfaces of the wall of the kiln, and arranged as described, for the purposes set forth.

H. R. FELL.
